Attorney

UNITED STATES PATENT OFFICE.

ROBERT F. KING, OF BOZEMAN, MONTANA.

COMBINED SINGLETREE AND SPREADER.

SPECIFICATION forming part of Letters Patent No. 645,475, dated March 13, 1900.

Application filed August 16, 1899. Serial No. 727,394. (No model.)

To all whom it may concern:

Be it known that I, ROBERT F. KING, a citizen of the United States, residing at Bozeman, in the county of Gallatin and State of Montana, have invented certain new and useful Improvements in a Combined Singletree and Spreader; and I do declare the following to be a full, clear, and exact description of the invention, such as will enable others skilled in the art to which it appertains to make and use the same, reference being had to the accompanying drawings, and to the letters of reference marked thereon, which form a part of this specification.

This invention relates to new and useful improvements in singletree and spreader attachments; and it consists in the provision of a spreader-bar carrying at its ends clevises which are connected to the singletrees and to which crotch-chains are connected. By this construction strain will be equally distributed, and owing to the peculiar construction of the spreader-bar the latter is prevented from bending.

The invention has for a further object the provision of an improvement in means heretofore employed for attaching traces to the whiffletrees.

To these ends and to such others as the invention may pertain the same consists in the peculiar construction and in the novel combination, arrangement, and adaptation of parts, all as more fully hereinafter described, shown in the accompanying drawings, and then specifically defined in the appended claims.

The invention is clearly illustrated in the accompanying drawings, which with the letters of reference marked thereon form part of this application, and in which drawings—

Figure 1 is a top plan view of my improved spreader-bar with singletree attachments. Fig. 2 is a rear view of the same. Fig. 3 is a transverse section upon the line 3 3 of Fig. 4. Fig. 4 is an enlarged detail in perspective of one end of the singletree, showing the trace-hook and its connections. Fig. 5 is an enlarged detail in perspective of the channel-plate attachment to the singletree, and Fig. 6 is an enlarged detail in perspective of a modified form of clevis attachment.

Reference now being had to the details of

the drawings by letter, A designates the spreader-bar, which is made, preferably, of a single piece of metal bent upon itself at its middle portion and having perforations *a* at each end. At the middle portion of the said bar is a rod B, which is provided to keep the two longitudinal sections of the spreader-bar at a given distance apart and prevent same from spreading. Carried on the pins C in the perforations *a* in said bar A are the clevis members D and D', the former of which has one end contracted with a recess D², which is provided to allow one end of the crotch-chain to be attached to the pin on which said clevis member is mounted. This member D passes over the singletree E and has a bearing in the channelled plate F, secured to the forward edge of the singletree. This plate is made, preferably, of a malleable metal, so that after the clevis member has been inserted in the channel of the plate the upwardly-extending portions may be bent over the member and partially, if not entirely, inclose same, as shown in the drawings. By this construction it will be noted that the singletree will have a slight longitudinal movement. At the opposite end of the spreader-bar the clevis member D' is slightly modified from the construction shown in the member D. Said clevis member D' has a contracted end, which is pivoted to the spreader-bar, and a recess similar to member D, in which an end of a crotch-chain engages; but instead of having a pivotal connection with the plate mounted on a singletree the clevis member D' has two laterally-extending wings d', which are perforated, and pins or bolts K, passed through said perforations and into the singletree, thus holding the clevis member rigid.

At the ends of the singletree are the ferrules M, which have diametrically-opposite lugs N, which are provided to retain the whiffletree-hooks R.

T are springs which are provided at the ends of the singletree. Each of these springs consists of a flat strip of spring metal, the body portion of which is preferably of a width corresponding with the thickness of the singletree-bar. These springs are attached at their inner ends securely to the upper face of the singletree-bar at points near the ends of said

bar, and the body portions of the springs are curved upwardly, and their free ends, which are downwardly inclined, are provided with hooks T'. The whiffletree-hooks R are provided with an enlarged looped body, which portion of the body engages the hook T' of the spring T and serves to normally hold the hook back against the end of the singletree. The lugs N upon the ferrule M at the end of the singletree serve to prevent the possibility of the hook being laterally displaced, as will be readily understood.

Having thus described my invention, what I claim to be new, and desire to secure by Letters Patent, is—

1. A combination singletree and spreader-bar, consisting of opposite longitudinal members spaced apart at their middle portions by a transverse rod, singletree-clevises pivoted to each end of said bar, singletrees to which said clevises are connected, and crotch-chains secured to the ends of said bar, as set forth.

2. In combination with the spreader-bar, having a rod secured to the longitudinal portions of the bar to hold same at a given distance apart, the clevis members having their

contracted ends pivoted to said bar, and provided with recesses, the crotch-chains mounted on the pin on which the clevises are pivoted, and in said recesses, as set forth. 30

3. In combination with the spreader-bar, the clevis member D having a contracted end which is recessed, and pivoted to the end of the spreader-bar, the singletree and channeled plate secured thereto, in which plate 35 said singletree has a bearing, the upwardly-extending projections of said plate being bent over the bearing portion of the clevis, as set forth.

4. The combination with a spreader-bar, of 40 a clevis having a recessed lug disposed between the members of said bar, a pivot-pin passing through said bar and lug, a crotch-chain secured to said pin within the recess of said lug, and a singletree extending through 45 said clevis, as set forth.

In testimony whereof I affix my signature in presence of two witnesses.

ROBERT F. KING.
